US0D1000743S

(12) **United States Design Patent** (10) **Patent No.:** **US D1,000,743 S**
Lei (45) **Date of Patent:** **** Oct. 3, 2023**

(54) **MOP BUCKET**

(71) Applicant: **Shenzhen Changping Network Technology Co., Ltd.**, Guangdong (CN)

(72) Inventor: **Jun Lei**, Chengdu (CN)

(73) Assignee: **SHENZHEN CHANGPING NETWORK TECHNOLOGY CO., LTD.**, Shenzhen (CN)

(**) Term: **15 Years**

(21) Appl. No.: **29/874,312**

(22) Filed: **Apr. 18, 2023**

(51) **LOC (14) Cl.** **07-05**

(52) **U.S. Cl.**

USPC **D32/53**

(57) **CLAIM**

The ornamental design for a mop bucket, as shown and described.

DESCRIPTION

FIG. 1 is a front, left and top perspective view of a mop bucket, showing my new design;

FIG. 2 is a rear, right and bottom perspective view thereof;

FIG. 3 is a front view thereof;

FIG. 4 is a rear view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines depict portions of the mop bucket in which the design is embodied that form no part of the claimed design.

1 Claim, 8 Drawing Sheets
